UNITED STATES PATENT OFFICE.

HENRY DANIEL O'BRIEN, OF FORSYTH, MONTANA.

TRUSS.

1,106,314.

Specification of Letters Patent.

Patented Aug. 4, 1914.

Application filed April 7, 1914. Serial No. 830,251.

To all whom it may concern:

Be it known that I, HENRY DANIEL O'BRIEN, a citizen of the United States, residing at Forsyth, in the county of Rosebud and State of Montana, have invented a new and useful Truss, of which the following is a specification.

The device forming the subject matter of this application is a truss, and one object of 10 the invention is to improve the belt portion of the truss so that the same will hold a truss pad readily in place.

Another object of the invention is to provide novel means for holding the pad upon 15 the belt.

Another object of the invention is to improve the truss pad.

With the above and other objects in view which will appear as the description proceeds, the invention resides in the combination and arrangement of parts and in the details of construction hereinafter described and claimed, it being understood that changes in the precise embodiment of the 25 invention herein disclosed, can be made within the scope of what is claimed, without departing from the spirit of the invention.

In the accompanying drawing:—Figure 1 shows in perspective a truss constructed in 30 accordance with the present invention; Fig. 2 is a transverse section through the belt and the pad, the latter appearing in elevation; Fig. 3 is a fragmental transverse section taken approximately on the line 3—3 35 of Fig. 1; Fig. 4 is a fragmental front elevation of the belt and pad; Fig. 5 is a transverse section of the pad; Fig. 6 is a transverse sectional detail illustrating a modified form of the invention.

40 In carrying out the present invention there is provided a belt including a band 1. The band 1 preferably is fashioned in a continuous length but it may be divided and united by any suitable means, such as a 45 buckle, as is common in the art, if desired, these details being well within the scope of a skilled mechanic and requiring no illustration. The band 1 ordinarily is fashioned from resilient material, rubber being preferred. The lower edge of the band 1 is 50 turned upwardly to form a reinforcing rib 2. The upturned edge of the band 1 which forms the ribs 2 may be held in place in any suitable manner. It may be cemented 55 to the body portion of the band, if desired.

A primary reinforcing strip 4 is secured

to the outer face of the band 1. This reinforcing strip 4 may be a piece of rubber if desired and, preferably, the reinforcing strip 4 hereinafter referred to as the primary reinforcing strip is secured throughout its entire area, by cementing or otherwise to the outer face of the band 1.

The invention includes a secondary reinforcing strip denoted generally by the 60 numeral 11. This strip 11 preferably is substantially co-extensive in width with the primary reinforcing strip 4 and, like the primary reinforcing strip 4, may be made of rubber. The secondary reinforcing strip 65 11 is carried in a continuous length across the lower edge of the band 1 and includes an outer layer 5 and an inner layer 6, between which layers, the primary reinforcing strip 4 and a portion of the band 1 are 70 inclosed. The layer 5 of the secondary reinforcing strip 11 preferably, is secured by cement or otherwise, to the primary reinforcing strip 4 throughout the entire area 75 of the latter. The ends of the rib 2 are 80 firmly attached as shown at 3 to the edges of the layer 5. The upper extremity of the inner layer 6 of the secondary reinforcing strip 11 is secured as shown at 7, by cement or otherwise, to the inner face of the band 1 85 and by the construction above outlined, the lower end portion of the inner layer 6 constitutes an open ended pad pocket, indicated by the reference numeral 8. There are aligned openings 9 in the layers 5 and 6 of 90 the secondary reinforcing strip 11, in the primary reinforcing strip 4 and in the band 1, all of which will be understood readily from Fig. 2.

The pad 10 may be of any desired construction but in one form of the invention the pad takes the form of a resilient hollow ball, as shown in Fig. 5, the pad being of rubber if desired. The construction of the pad, however, may be changed from that 100 shown in the drawings without jeopardizing the utility of the invention.

In practical operation, the pad 10 whatever its form may be, is thrust into the open ended pad pocket 8 and is retained in place 105 by becoming lodged in the openings 9. The resilient band 1 serves to hold in place the pad 10 so that the latter will retain the rupture properly.

The layer 6 of the secondary reinforcing 110 strip 11 forms a pad pocket, as hereinbefore described, and the outer layer 5 of the sec-

ondary reinforcing strip together with the primary reinforcing strip 4 serve to stiffen up the band 1 and to render the same effective in holding the pad 10 in place upon the 5 rupture.

Referring to the modification shown in Fig. 6, parts hereinbefore described are referred to by reference characters previously used, with the suffix "a." The modification 10 shown in Fig. 6 consists in omitting the openings in the parts 5^a, 4^a and 1^a, the opening 9^a being formed in the part 6^a only. This construction, obviously, gives the band portion of the device a greater binding or 15 holding efficiency.

Having thus described the invention, what is claimed is:—

1. In a truss, a band; a primary reinforcing strip applied transversely to one face of 20 the band; a secondary reinforcing strip substantially co-extensive in lateral extent with the primary reinforcing strip, the secondary reinforcing strip being extended in a continuous extent across one edge of the band 25 and including spaced layers between which the primary reinforcing strip and a portion of the band are inclosed, one layer of the secondary reinforcing strip being secured to the primary reinforcing strip throughout an 30 area substantially co-extensive with the primary reinforcing strip, the other layer of the secondary reinforcing strip being secured to the band along the end of said layer only to define an open ended pad pocket, 35 both layers of the secondary reinforcing strip, the primary reinforcing strip and the band having aligned openings; and a pad insertible into the pocket through the open 40 ends thereof, the pad being engaged in the openings.

2. In a truss, a band; a primary reinforce-

ing strip applied to one face of the band; a secondary reinforcing strip extended in a continuous length across one edge of the band and including spaced layers between 45 which the primary reinforcing strip and a portion of the band are inclosed, one layer of the secondary reinforcing strip having an opening and being secured adjacent its end only to the band to define an open ended pad 50 pocket about the opening; and a pad in the pocket and engaged in the opening.

3. In a truss, a belt; a U-shaped strip extended in a continuous length transversely of the belt and across one edge of the belt 55 and comprising spaced layers between which the belt is inclosed, one layer being secured adjacent its end only to the belt to define a pocket open along its upright edges, said layer having an opening; a pad in the pocket 60 and lodged in the opening.

4. In a truss, a belt; a U-shaped strip extended in a continuous length transversely of the belt and across one edge of the belt and comprising spaced layers between which 65 the belt is inclosed, one layer being secured adjacent its end only to the belt, to define a pad pocket open along its upright edges; and a pad lodged in the pad pocket.

5. In a truss, a belt; a U-shaped strip extended in a continuous length transversely of the belt and across one edge of the belt and comprising spaced layers between which 70 the belt is inclosed; and a pad lodged between the belt and one layer of the strip. 75

In testimony that I claim the foregoing as my own, I have hereto affixed my signature in the presence of two witnesses.

HENRY DANIEL O'BRIEN.
